UNITED STATES PATENT OFFICE.

CHARLES SMITH HUNTINGTON AND ARTHUR SHARP HUNTINGTON, OF
OMAHA, NEBRASKA.

DESIGN FOR A LEGGING.

SPECIFICATION forming part of Design No. 30,703, dated May 2, 1899.

Application filed February 6, 1899. Serial No. 704,740. Term of patent 14 years.

To all whom it may concern:

Be it known that we, CHARLES SMITH HUNTINGTON and ARTHUR SHARP HUNTINGTON, of Omaha, in the county of Douglas and State of Nebraska, have invented and produced a new and original Design for a Legging, of which the following is a full, clear, and exact specification.

Reference is to be had to the accompanying drawings, forming a part of this specification, in which similar characters of reference indicate corresponding parts in all the views.

Figure 1 is a side elevation of a legging, showing our design. Fig. 2 is a front elevation of the same, and Fig. 3 is a sectional plan view of the same on the line 3 3 in Fig. 1.

The design consists of the body A, of unbroken continuity and having the instep portion B set off from the body, the inner ends 20 of the instep portion overlapping the instep

end of the body and having a binding C, and a row of stitches appears on the inner edge of the instep portion B, said binding extending from one side of the lower end of the body A to the other side thereof in a curved line 25 following approximately the line of the instep.

The legging is provided with the fastenings D, and upon the heel portion of the body A is the curved stiffening-band F appearing as 30 raised or set off from the body.

We claim—

The design for a legging herein shown and described.

CHARLES SMITH HUNTINGTON.
ARTHUR SHARP HUNTINGTON,
